UNITED STATES PATENT OFFICE.

NATHAN H. HEFT, OF BRIDGEPORT, CONNECTICUT.

RAILWAY-TRUCK.

SPECIFICATION forming part of Letters Patent No. 680,587, dated August 13, 1901.

Application filed May 2, 1901. Serial No. 58,455. (No model.)

To all whom it may concern:

Be it known that I, NATHAN H. HEFT, a citizen of the United States, residing at Bridgeport, county of Fairfield, State of Connecticut, have invented a new and useful Railway-Truck, of which the following is a specification.

My invention has for its object to provide a railway-truck adapted for use on either steam or electric railways, and especially adapted for use on electric railways where heavy cars are required to be run at a high speed over a rough and uneven road-bed, important features of novelty in my improved truck being that the bolster, elliptical springs, and spring-plank are suspended by means of swing-links from the mid-length of levers which I term "secondary" equalizing-bars, the inner ends of said secondary equalizing-bars being suspended from the transom and the outer ends of said secondary equalizing-bars being pivotally connected by means of swing-links to other equalizing-bars, which I term the "primary" equalizing-bars, there being in each truck four secondary equalizing-bars and two primary equalizing-bars, and the ends of the primary equalizing-bars resting upon coil-springs, which themselves rest upon the side frames. Numerous advantages result from and are peculiar to my novel construction. It is deemed sufficient for the purposes of this specification to mention that the weight of the truck as a whole is much less than that of any truck of this character heretofore placed upon the market. The general construction and arrangement of parts are such that the truck as a whole is stronger and cheaper to build. The springs are all in pairs, and each spring carries an equal part of the weight. The spring travel of the bolster is nearly three times as great as in any truck heretofore devised, it being understood, of course, that in using the term "bolster" I include by implication the car-body as well, which is attached to the bolster in the ordinary or in any preferred manner, but is not shown in the drawings, as it forms no portion of my present invention.

Another and vitally-important feature of my invention and one that is wholly new is that in use upon curves and upon rough road-beds the bolster maintains its horizontal po-

sition—that is, its parallelism to the plane of the horizon—and does not rise and fall with the wheels, side frames, and transom.

55

Other important advantages resulting from my novel construction are that, owing to the fact that the primary equalizing-bars are recessed within the side frames, I am enabled to make the journal-box springs longer and much more resilient than has heretofore been possible, thereby giving greater vertical play, I am enabled to check the lateral movement of the body without a blow and without the interposition of buffer-springs, and I am enabled to dispense with the use of end frames to keep the truck in alignment.

60

The important benefits resulting from the use of my novel truck may be generalized under two main heads—first, ease of riding and greatly-increased comfort to passengers, owing to increased spring motion and reduced motion of the body, rising and falling of the bolster and car-body, as well as lateral and swaying movements, being practically eliminated, and, second, that owing to the greatly-increased spring travel and the novel mode in which the bolster is supported the blows of the wheels at the joints are almost completely dissipated—*i. e.*, taken up during their transmission through the springs—whereby the life of the truck is greatly increased and the cost of maintenance not only of the track-rails, but of the wheels, axles, springs, truck-frames as a whole, and car-bodies as a whole, is enormously reduced. My invention thus enables me to simultaneously reduce the cost of construction, reduce the cost of maintenance, and add greatly to the ease and comfort of passengers.

75

In order to clearly understand the principle of my invention, it should be borne in mind that each time a wheel strikes a track-rail joint more or less of a blow is given. If the road-bed is rough and uneven or the rails have sunk at the joints, these blows materially shorten the life of the track-rails, the trucks, and the car-bodies. Each blow is transmitted through the journal-boxes to the side frames and from the side frames through intermediate parts to the bolster and car-body.

80

In my improved truck the novel mode in which the bolster is supported and the inter-

85

90

95

100

position between the spring-plank and the side frames of primary and secondary equalizing-bars, sets of spring-links, and coil-springs largely dissipate—i. e., take up—
5 these blows before they reach the bolster and practically eliminate as a destructive agent to the track-rails the return blow of the body to the rails.

In order to accomplish the desired results, 10 I have devised the novel truck, which I will now describe in detail, referring to the accompanying drawings, forming part of this specification, and using reference characters to designate the several parts.

15 Figure 1 is a side elevation of my novel truck; Fig. 2, a transverse section on the line 2 2 in Fig. 1 looking toward the right, the truck being indicated as upon a level road-bed; Fig. 3, a similar view illustrating the 20 action of the secondary equalizing-bars and swing-links in retaining the spring-plank and bolster in their normal horizontal position when one side of the truck is depressed, as upon a curve or an uneven road-bed; Fig. 4, 25 a transverse section on the line 4 4 in Fig. 2 looking toward the left; Fig. 5, a transverse section of one of the side frames on the line 5 5 in Fig. 1 looking toward the right, an equalizing-bar spring appearing in elevation; 30 and Fig. 6 is a detail plan view on the line 6 6 in Fig. 5.

20 denotes the side frames; 21, the transom; 22, the bolster; 23, the primary equalizing-bars; 24, the secondary equalizing-bars, 35 and 25 the spring-plank. The side frames and the transom are formed from plates of rolled steel securely bolted together, filling-pieces being placed between the side plates, wherever required, to give the necessary 40 strength. I have shown the side frames as closed at the top and open at the bottom. These details of construction, however, are not of the essence of my invention, it being immaterial of how many plates the side 45 frames and transom are composed or the special manner in which they are bolted together. It is essential, however, that each side frame be provided with a longitudinal recess 26 between the side plates in which the 50 corresponding primary equalizing-bar lies, this construction being compact and strong and enabling me to use longer and more resilient equalizing-bar springs 27 than it has heretofore been possible to use.

55 28 denotes track-rails; 29, wheels; 30, axles; 31, boxes in which the axles are journaled and which lie in recesses 32 in the side frames, and 33 journal-box springs which are interposed between the journal-boxes and the side 60 frames. The side frames are provided with recesses, as at 50, (see Fig. 1,) to receive the equalizing-bar springs 27. These springs are seated in cups 34, which rest upon and are rigidly secured to the side frames at the bottom of the recesses, the upper ends of said 65 springs resting in inverted cups 35, which are made integral with or rigidly secured to the

under sides of heads 36 at the ends of the primary equalizing-bars, said equalizing-bars being supported wholly by said springs. Vertical bolts 37 are shown as extending through the side frames, equalizing-bar springs, heads 36, the cups, and through-clips 38 on the under side of the side frames. It will be noted in Fig. 5 that the heads 36 at the ends of the 75 primary equalizing-bars are free to move vertically in recesses 26 in the side frames.

The bolster, which I have indicated by 22, lies within the transom 21, but is wholly independent thereof, (see Fig. 4,) and rests upon 80 bolster-clamps 39, by which it is secured to the tops of elliptical springs 40. These elliptical springs rest upon and are secured to spring-cradles 41, which in turn are secured to cross-heads 42 at the ends of spring-plank 85 25, the side frames being provided with recesses, as at 51, to give clearance to the ends of the springs.

The secondary equalizing-bars, which I have indicated by 24, are a vitally-important part 90 of my invention. The cross-heads 42 at the ends of the spring-plank are pivoted to the lower ends of swing-links 43, the upper ends of said swing-links being pivoted to the mid-length of the secondary equalizing-bars. (See 95 Fig. 4 in connection with Fig. 2.) The inner ends of the secondary equalizing-bars are pivoted to swing-links 44, the upper ends of which are pivoted by means of bolts 46 to brackets 45, which are themselves rigidly 100 bolted to the transom.

47 denotes the motor-support bars, which are also carried by bolts 46, (see Figs. 2 and 4,) said bolts passing through elongated openings 48 in order to permit slight lateral movement of the motor-support bars without strain upon the brackets and bolts. The outer ends of the secondary equalizing-bars are pivoted to yokes 49, which are rigidly secured to and extend upward from the mid-length of the 110 primary equalizing-bars. (See Fig. 1 in connection with Figs. 2 and 4.)

The operation of my novel truck in use will, it is thought, be readily understood by comparing Fig. 3 with Fig. 2, the latter showing 115 the truck upon a level road-bed and the former showing clearly the position on an inclined road-bed of the secondary equalizing-bars, the spring-plank, and the swing-links, whose operation insures that the bolster, and consequently the car-body, will maintain its normal horizontal position, even though one side frame be considerably lower than the other, so that the transom is at a perceptible incline to the horizontal plane. In order to clearly 120 understand how this parallelism of the bolster to the horizontal plane is maintained when the transom lies at an inclination to the horizontal plane, it must be borne in mind that the spring-plank, the elliptical springs, 125 and the bolster instead of being suspended directly from the transom are suspended by means of swing-links from the mid-lengths of 130 secondary equalizing-bars, the inner ends of

said secondary equalizing-bars being suspended by means of swing-links from the transom and their outer ends being connected by means of swing-links with the primary 5 equalizing-bars, themselves resting upon coil-springs, which in turn rest upon the side frames.

Having thus described my invention, I claim—

1. In a railway-truck, the combination with a bolster, a transom and side frames, of primary equalizing-bars carried by the side frames, secondary equalizing-bars pivotally connected to the outer ends of the primary 15 equalizing-bars, the inner ends of said secondary equalizing-bars being pivotally connected to the transom, elliptical springs upon which the bolster rests and a spring-plank upon which the elliptical springs rest and the 20 ends of which are pivotally suspended from the mid-lengths of the secondary equalizing-bars.

2. In a railway-truck, the combination with a bolster, a transom and side frames, of primary equalizing-bars the ends of which rest upon equalizing-bar springs which themselves rest upon the side frames, secondary equalizing-bars pivotally connected to the outer ends of the primary equalizing-bars, 25 the inner ends of said secondary equalizing-bars being pivotally connected to the transom, elliptical springs upon which the bolster rests and a spring-plank upon which the elliptical springs rest and the ends of which are pivotally suspended from the mid-lengths of the secondary equalizing-bars.

3. In a railway-truck, the combination with a bolster, a transom and side frames, of secondary equalizing-bars pivotally connected 40 at their outer ends to the primary equalizing-bars, swing-links by which the inner ends of the secondary equalizing-bars are connected to the transom, elliptical springs supporting the bolster, a spring-plank supporting the elliptical springs and swing-links by 45 which the ends of the spring-plank are connected to the mid-lengths of the secondary equalizing-bars.

4. In a railway-truck, the combination with a bolster, a transom and side frames having longitudinal recesses 26, of primary equalizing-bars lying in said recesses, springs upon which the ends of said primary equalizing-bars rest and which themselves rest upon the 50 side frames, secondary equalizing-bars pivotally connected to the primary equalizing-bars, the inner ends of said secondary equalizing-bars being pivotally connected to the transom, a spring-plank, elliptical springs supported by the spring-plank and themselves supporting the bolster and swing-links by which the ends of the spring-plank are connected to the mid-length of the secondary equalizing-bars.

5. The side frames comprising side plates having corresponding central recesses 51 and on opposite sides thereof corresponding re-

cesses 32 and 50 and between said side plates a longitudinal recess 26, substantially as shown, for the purpose specified.

70

6. In a railway-truck, the combination with side frames comprising side plates having recesses 50 and between said side plates longitudinal recesses 26, of primary equalizing-bars lying in recesses 26, the ends of said 75 equalizing-bars resting upon equalizing-bar springs lying in recesses 50 and supported by the side frames.

7. In a railway-truck, the combination with side frames comprising side plates having recesses 50 and cups 34 resting upon the side frames at the bottoms of the recesses and between said side plates longitudinal recesses 26, of primary equalizing-bars lying in recesses 26, the ends of said bars being provided 85 with heads carrying inverted cups 35, and equalizing-bar springs resting upon cups 34 and carrying cups 35 and the primary equalizing-bars.

80

8. In a railway-truck, the combination with 90 a transom and primary equalizing-bars, of a bolster, elliptical springs by which it is supported, a spring-plank upon which the elliptical springs rest, and secondary equalizing-bars whose inner ends are pivotally connected 95 to the transom, whose outer ends are pivotally connected to the primary equalizing-bars and from whose mid-lengths the spring-plank, elliptical springs and bolster are pivotally suspended.

100

9. In a railway-truck, the combination with a transom and primary equalizing-bars, of a bolster, elliptical springs by which it is supported, a spring-plank having at its ends cross-heads upon which the elliptical springs 105 rest, secondary equalizing-bars whose outer ends are pivotally connected to the primary equalizing-bars, swing-links connecting the inner ends of the secondary equalizing-bars with the transom and other swing-links connecting the cross-heads on the spring-plank with the mid-lengths of the secondary equalizing-bars.

110

10. In a railway-truck, the combination with a transom, a bolster within the transom 115 but free to move independently thereof, and elliptical springs supporting the ends of the bolster, of primary equalizing-bars, a spring-plank which supports the elliptical springs and secondary equalizing-bars whose outer 120 ends are pivotally connected to the primary equalizing-bars, whose inner ends are pivotally suspended from the transom and from whose mid-lengths the ends of the spring-plank are pivotally suspended.

125

11. In a railway-truck, the combination with side frames, a transom, two primary equalizing-bars and four primary equalizing-bar springs intermediate said equalizing-bars and the side frames, of a bolster, four elliptical springs upon which the bolster rests, a spring-plank upon which the elliptical springs rest, and four secondary equalizing-bars whose inner ends are pivotally connected to

130

the transom, whose outer ends are pivotally connected to the primary equalizing-bars and from whose mid-lengths the spring-plank, elliptical springs and bolster are pivotally suspended.

12. In a railway-truck, the combination with side frames, axles, springs intermediate the side frames and the axles, primary equalizing-bars and springs intermediate the primary equalizing-bars and the side frames, of a transom, a bolster, elliptical springs by which the bolster is supported, a spring-plank upon which the elliptical springs rest, and secondary equalizing-bars whose inner ends are pivotally connected to the transom, whose outer ends are pivotally connected to the primary equalizing-bars and from whose mid-lengths the spring-plank, elliptical springs and bolster are pivotally suspended, said three sets of springs being in pairs and each spring carrying an equal share of the weight.
13. In a railway-truck, the combination with a transom and a spring-plank, of secondary equalizing-bars from whose mid-lengths the ends of the spring-plank are pivotally suspended, and primary equalizing-bars to which the outer ends of the secondary equalizing-bars are pivotally connected, the inner ends of said secondary equalizing-bars being pivotally suspended from the transom.

14. In a railway-truck, the combination with a transom and a spring-plank, of secondary equalizing-bars, swing-links intermediate the mid-lengths of the secondary equalizing-bars and the ends of the spring-plank, other

swing-links intermediate the inner ends of the secondary equalizing-bars and the transom, and primary equalizing-bars to which the outer ends of the secondary equalizing-bars are pivotally connected.

40

15. In a railway-truck, the combination with a transom, a bolster, a spring-plank and elliptical springs intermediate the bolster and the spring-plank, of secondary equalizing-bars from whose mid-lengths the ends of the spring-plank are pivotally suspended and primary equalizing-bars to which the outer ends of the secondary equalizing-bars are pivotally connected, the inner ends of said secondary equalizing-bars being pivotally suspended from the transom.

45

16. In a railway-truck, the combination with a transom and a spring-plank, of secondary equalizing-bars from whose mid-lengths the ends of the spring-plank are pivotally suspended, primary equalizing-bars to which the outer ends of the secondary equalizing-bars are pivotally connected, the inner ends of said secondary equalizing-bars being pivotally suspended from the transom, side frames, and coil-springs intermediate the ends of the primary equalizing-bars and the side frames.

50

In testimony whereof I affix my signature in presence of two witnesses.
